UNITED STATES PATENT OFFICE

SAMUEL I. COLE, OF NEW YORK, N. Y., ASSIGNOR TO AEROVOX WIRELESS CORPORATION,
A CORPORATION OF NEW YORK

CONDENSER

Application filed April 2, 1925. Serial No. 20,081.

The invention relates more especially to condensers of small and fixed capacity for radio use, although the invention is not limited to such application.

5 It is among the objects of the invention to provide a condenser of the type mentioned which shall be easy to manufacture, of rugged construction, the capacity of which is substantially invariant in all conditions of handling 10 and use, which shall be susceptible of being readily mounted without the need for tools other than a screw driver, which shall not be dependent for operativeness on exerting a clamping pressure on the pack, and which 15 shall be substantially proof against tampering.

I preferably employ a condenser pack which is preformed under pressure and heat so that the laminated foil sheets of the pack 20 take a firm set and the dielectric laminations of the pack become adherently fastened together, as described and claimed in the co-pending application of Samuel Siegel, Serial No. 750,966 filed November 20, 1924.

25 My invention is concerned more especially with protective and terminal structures for the pack, I fold the foil sheets about the ends of insulating backing sheets and provide metallic terminal plates in contact with said 30 folded over foil sheets. Terminal posts extend through the pack and the terminal plates maintaining said parts assembled, without however, affecting the capacity of the pre-formed stack. In the preferred embodiment, 35 the terminal plates are bowed, so that in tightening the posts in position, the bowed sheets will become flattened and exert pressures primarily at the edges of the backing sheets to prevent the same from curling or 40 warping, the posts being preferably constructed and arranged to avoid any substantial 45 pressure on the preformed stack.

To avoid rocking of the plates about the 45 terminal posts, said plates are preferably provided with lateral ears overlapping the edges of the backing plates. For mounting a grid leak, I employ auxiliary supporting angle brackets therefor which may be secured 50 in place by the terminal posts, and having a lateral edge maintained against rocking by

engagement with the slightly protruding edge of the preferably angle-shaped terminal plate.

The invention may be more fully understood from the following description in connection with the accompanying drawings 55 wherein:

Figure 1 is a perspective view of a condenser embodying the invention,

Figure 2 is a similar view with the reverse 60 side of the condenser exposed,

Figure 3 is an enlarged transverse section on the line 3—3 of Figure 1,

Figure 4 is a disassembled perspective view 65 of the two securing plates,

Figures 5 and 6 are sectional views on the line 6—6 of Figure 2, Figure 5 indicating the position of the parts before a riveting operation and Figure 6 indicating the position 70 of the parts after a riveting operation,

Figure 7 is a perspective view of a modified form of condenser,

Figure 8 is a view similar to Figure 7 showing the reverse side of the condenser, 75 and

Figure 9 is a perspective view of one of the securing plates.

The individual elements of the pack, as well as the backing sheets may be of familiar construction including foil sheets 11 inter- 80 leaved with thin sheets 12 preferably of mica or similar thin flexible dielectric material with the ends of alternate foil sheets projecting beyond opposite edges of the pack and folded over the edge of one of the backing 85 sheets 10 as indicated at 18, (Figure 3). Thus the ends of all the foil sheets having like polarity may be electrically connected together by the use of suitable terminal posts 14 which may serve both as supports and as convenient 90 points of attachment for electrical conductors.

Preferably, as set forth and claimed in the copending application above referred to, the 95 various foil sheets and dielectric sheets are impregnated with paraffine and subjected to pressure and heat, as by heated plates or rollers. Excess paraffine is thereby squeezed out, and the parts take a firm set and become ad- 100herently connected together.

The stack is protected according to my invention, and adapted for ready mounting by placing it between two plates 10 of bakelite or similar insulating material. The alternate 5 foil sheets are bent over the outside of the backing sheets and terminal contact is established by means of angle-shaped terminal plates 15, which are superposed over one of the backing plates and have upstanding edges 10 protruding beyond the other backing plate, there being a complementary generally flat metal plate 16 superposed over the other backing plate. In the preferred embodiment the superposed plates 16 and, if desired, also 15 the angle plates are initially bowed as best shown in Figure 5, and the assembly is completed by means of headed terminal posts 19 contacting the angle plate as at 21 having hollow shanks extending through corresponding 20 apertures in the stack and turned or rolled over at their ends as at 23, by that operation flattening the curved plate 16 as best shown in Figures 6. The rolling over tool is preferably so constructed that in the 25 process of operation, the extent of depression is limited so that the curved plate will only be approximately flattened without exerting any additional direct downward pressure upon the stack. As a consequence while the 30 terminal post serves to effect a sufficient electrical contact between the plate 15 and the turned-over ends of the foil, yet no material direct pressure is thereby exerted upon the stack, and, as tests have repeatedly shown, the 35 capacity of the stack after it has been assembled, is precisely the same as it was when the stack itself was completed and before applying the backing sheets, the terminal plates and the assembling posts.

40 Another feature of importance is the provision of tongues 25, 26 at the edges of the arm 17 of securing plate 15 at the ends of plate 16, said tongues embracing the lateral edges of the stiff backing sheets and positively 45 preventing rocking displacement of either of the securing plates about the securing devices 14 as centers. By preventing such displacement, I eliminate the possibility of altering, injuring, or losing the electrical contact between the terminal ends of the folded foil 50 sheets and the terminal plates, which might otherwise be incurred in the ordinary course of packing, transportation, installation or use. It will be noted that the edge of the 55 angle plate protrudes beyond the companion plate 16 so as to render possible the use of the same plates for assembling stacks of different thicknesses or of different capacities.

In the application to grid condensers, it is 60 preferred to mount a grid leak resistance across the terminals thereof, and for this purpose, I have provided a special construction of mounting clip now to be described. This clip comprises a pair of angle plates 40 which 65 may be secured in position against the plates

15 by the same binding post attaching means 23 which secured the stack, the backing plates and the terminal plates in assembled relation. Inasmuch as the length of the grid leak 70 resistance may be greater than that of the condenser the upstanding arms of the bracket protrude beyond the condenser and an angle-shaped dent 41 is formed at the angle of the bracket, the upstanding part 42 of said dent contacting the upstanding edge of 75 the terminal plate. By this arrangement as will be readily seen, the terminal brackets are securely held against rocking about the securing member, the terminal angle plate itself being held by the upstanding lugs 42 against rocking about the securing member 80 as an axis. This relation of parts moreover, makes for ease of assembly and precludes incorrect assembly.

In Figures 7 to 9, I have illustrated a modified construction in which a plate of semi-tray shape is employed comprising side sections 28 integrally connected to end section 29 and cover or plate section 30. Section 30, which overlies one of the backing sheets, is 85 bowed to prevent undue pressure and warping of the latter, when the post ends are turned over. In this case, the heads 21 of the securing devices hold one of the backing sheets and the turned over ends 23 of the 90 tubular sections 20 of the securing devices hold the securing plates, and also preferably clamp terminals 32 to the securing plates. These terminals are of usual type, suitable for 95 soldering attachment to electrical conductors forming the condenser leads, and may, of course, also be used in the embodiment of Figures 1 to 6.

The tapped posts in both embodiments 100 may be used as electrical binding posts or as 105 mounting posts or for both purposes concurrently. For each use, a screw need merely be threaded thereinto, without the need for a nut, which would be necessary were the post or other fastening element merely perforated 110 and not tapped.

In connection with the foregoing description, it will be noted that in every case, I perform and press the condenser pack and assemble it as a unit and thus guard against the 115 necessity for exerting pressure on the pack during assembly, which might produce undesirable changes in capacity or by varying the compression on a portion or portions of 120 the pack. In every case, I have guarded against any slippage of the terminal clips which might result in a faulty electrical connection between the clips and the ends of the foil sheets. In every case, also, I safeguard 125 against warping of the backing sheets and provide for the ready attachment of electrical conductors. Means are provided for both supporting the condensers and attaching lead wires, since the securing devices may 130

be optionally used either as supports or terminals.

Having thus described my invention, what I claim as new and desire to secure by Letters Patent is:—

- 5 1. A condenser including backing sheets of relatively stiff insulating material, a condenser pack between the sheets, pairs of co-operating securing plates disposed on opposite sides of the sheets, and held against relative separation by securing devices passing through the plates, sheets and pack, said securing devices each having one end upset over one of the securing plates and their 10 other ends headed, and internally threaded to receive a supporting screw. 75
- 20 2. A condenser comprising in combination, a condenser stack, angle shaped terminal plates super-posed over one side of the stack and having their edges in contact with the ends of the stack, and protruding therebeyond, upstanding terminal brackets super-posed over the stack on the side opposite said terminal plates and having a portion 25 extending lengthwise of said protruding edge, cylindrical fastening members penetrating said stack, said terminal plate and said bracket, said terminal plate having lateral tongues embracing the stack whereby 30 the various parts will be maintained against 80 rocking displacement about said cylindrical fastening element. 90
- 30 3. A condenser comprising a stack of alternating, conducting and insulating sheets, insulating backing sheets for said stack, angle-shaped terminal plates, and having an arm superposed over one of said backing plates, and the other arm extending across the end of the stack, and protruding therebeyond, 35 terminal brackets for a grid leak resistance of greater length than said condenser, said brackets being angle-shaped and including a dented portion extending the width of and contacting with the protruding terminal 40 plates for a grid leak resistance of greater length than said condenser, said brackets being angle-shaped and including a dented portion extending the width of and contacting with the protruding terminal 45 plates, and cylindrical fastening members penetrating the stack, the bracket and the terminal portions. 105
- 40 4. A condenser comprising a stack of alternating, conducting and insulating sheets, insulating backing sheets for said stack, angle shaped terminal plates, and having an arm superposed over one of said backing plates, and the other arm extending across the end of the stack, and protruding therebeyond, 45 terminal brackets for a grid leak resistance of greater length than said condenser, said brackets being angle shaped and including a dented portion extending the width of the protruding terminal plate portion, cylindrical fastening members penetrating the stack, the bracket, and the terminal portions, and lugs on said terminal plate embracing the edges of the backing plates, whereby 50 the various parts will be retained against 110
- 55 5. A condenser comprising a stack of alternating, conducting and insulating sheets, insulating backing sheets for said stack, angle shaped terminal plates, and having an arm superposed over one of said backing plates, and the other arm extending across the end of the stack, and protruding therebeyond, 60 terminal brackets for a grid leak resistance of greater length than said condenser, said brackets being angle shaped and including a dented portion extending the width of the protruding terminal plate portion, cylindrical fastening members penetrating the stack, the bracket, and the terminal portions, and lugs on said terminal plate embracing the edges of the backing plates, whereby 65 the various parts will be retained against 115
- 65 6. A condenser comprising a stack of alternating, conducting and insulating sheets, insulating backing sheets for said stack, angle shaped terminal plates, and having an arm superposed over one of said backing plates, and the other arm extending across the end of the stack, and protruding therebeyond, 70 terminal brackets for a grid leak resistance of greater length than said condenser, said brackets being angle shaped and including a dented portion extending the width of the protruding terminal plate portion, cylindrical fastening members penetrating the stack, the bracket, and the terminal portions, and lugs on said terminal plate embracing the edges of the backing plates, whereby 75 the various parts will be retained against 120
- 75 7. A condenser comprising a stack of alternating, conducting and insulating sheets, insulating backing sheets for said stack, angle shaped terminal plates, and having an arm superposed over one of said backing plates, and the other arm extending across the end of the stack, and protruding therebeyond, 80 terminal brackets for a grid leak resistance of greater length than said condenser, said brackets being angle shaped and including a dented portion extending the width of the protruding terminal plate portion, cylindrical fastening members penetrating the stack, the bracket, and the terminal portions, and lugs on said terminal plate embracing the edges of the backing plates, whereby 85 the various parts will be retained against 125
- 85 8. A condenser comprising a stack of alternating, conducting and insulating sheets, insulating backing sheets for said stack, angle shaped terminal plates, and having an arm superposed over one of said backing plates, and the other arm extending across the end of the stack, and protruding therebeyond, 90 terminal brackets for a grid leak resistance of greater length than said condenser, said brackets being angle shaped and including a dented portion extending the width of the protruding terminal plate portion, cylindrical fastening members penetrating the stack, the bracket, and the terminal portions, and lugs on said terminal plate embracing the edges of the backing plates, whereby 95 the various parts will be retained against 130

Signed at New York, in the county of New York and State of New York, this 30th day of March, A. D. 1925. 70

SAMUEL I. COLE.
